UNITED STATES PATENT OFFICE.

EMERSON L. CLARK, OF LAKEWOOD, OHIO, ASSIGNOR TO NATIONAL CARBON COMPANY,
A CORPORATION OF NEW JERSEY.

COMPRESSION-RHEOSTAT.

1,202,161.

Specification of Letters Patent. Patented Oct. 24, 1916.

Application filed November 15, 1915. Serial No. 61,451.

To all whom it may concern:

Be it known that I, EMERSON L. CLARK, a citizen of the United States, residing at Lakewood, in the county of Cuyahoga and 5 State of Ohio, have invented a certain new and useful Improvement in Compression-Rheostats, of which the following is a full, clear, and exact description.

This invention relates to improvements in 10 rheostats of the type commonly known as compression rheostats, in which the resistance is due primarily to varying contact resistance of the elements when placed under variable pressure.

15 One of the objects of this invention is to secure rapid and efficient radiation of the heat generated with a simple construction of rheostat.

Another object of my invention is to increase 20 the range through which the resistance may be varied.

A further object of my invention is to prevent arcing at the points of support.

Another object is to provide means for 25 transmitting pressure uniformly over the contact area of the resistance plates.

In the present type of compression rheostats the resistors usually consist of a number of plates of carbon or other composition 30 suitably supported with the faces in contact. When it is desired to increase the range of a rheostat of this type, the ordinary method is to increase the number of plates. It is found, however, that the range 35 is not increased in the same proportion as the number of plates and the increase in the number of plates beyond certain limits is entirely impractical. This is due to the fact that if a long horizontal pile of such 40 resistors, compressed to the point of lowest resistance, is gradually relieved from pressure, the resistors at the end at which pressure is applied are almost entirely relieved from pressure and slide readily along the 45 support. Those at the other end, however, are always under some compression, because in order to expand they must overcome the frictional resistance of all of the plates resting edgewise on the supports. With a 50 rather long pile, in many cases the circuit will be opened at the compression end before the contact resistance of the plates at the rear end is appreciably increased. To eliminate this disadvantage and secure a 55 wide range with a relatively short rheostat,

an arrangement for overcoming the frictional resistance will be used to increase the upper limit of resistance and a mechanism for placing the sections in parallel will be used to obtain a low resistance.

Other features of the construction are shown in the drawings and set forth in the description in which:

Figure 1 is a plan view of my improved rheostat. Fig. 2 is a side view of Fig. 1. Fig. 3 is a cross section on a reduced scale on the irregular line A—A of Fig. 1. Fig. 4 is a detail view of the plate used at the pressure ends. Fig. 5 shows a partial cross section on the line B—B of Fig. 1. Fig. 6 is a partial cross section of the plates and support at the central point of support. Fig. 7 is a detail view of one of the plates used between the sections and as a contact plate. Fig. 8 is a view partially in section illustrating the position of certain members when the sections of the rheostat are in series. Fig. 9 is a view similar to Fig. 8 showing the same members when the sections are in parallel. Fig. 10 shows an arrangement for maintaining the contacts of the series-parallel switching device in certain positions.

Referring particularly to Figs. 1, 2 and 3 of the drawings, the frame of the rheostat 85 consists of two end members 1 and 2, preferably of metal, joined by side rods 3 and 4 and by a rod 5 below and between the side rods. These rods preferably consist of a body portion 6 of metal (Figs. 5 and 6) 90 covered with a coating 7 of vitreous enamel or other insulating material. The ends of the rods are fastened to and insulated from the end members, for example by means of insulating bushings 8 and nuts 9 threaded over the ends of the rods which are of reduced cross section.

The plates 10 of the rheostat are preferably circular and are staggered to provide radiating fins. This is done by placing the plates so that they all rest upon the central rod 5 with each alternate one touching the side rods 3 and 4 respectively. By suitably choosing the diameter of the disks and the spacing of the supporting rods, that part of the disks engaged in radiation of heat may be suitably proportioned. A satisfactory relation between the two is shown in Fig. 3 in which the portion of the disks constituting the resistance is shown in section. Ad- 110

jacent the end 1 of the rheostat is placed an insulating block 11 of the shape shown in Fig. 4 and also a metallic contact plate 12 as shown in Fig. 7, both of which are suitably formed to rest upon the rods 3, 4 and 5. Near the end 2 another insulating block 11 and contact plate 12 are similarly mounted on the supporting rods. The arrangement for applying pressure consists of a metal plate 13, a ball 14 adjacent thereto, a socket 15 for retaining the ball, and a frame 16 adapted to retain the ball and socket. The frame 16 and plate 13 are attached to the insulating member 12 by means of screws 17. Pressure is applied by means of a hand wheel 18 on a screw 19 threaded through a bearing 20 in the end plate 2. The end of the screw 19 is fastened to or made integral with the socket 15 and is reduced to fit into a slot 21 in the frame 16.

The resistance disks are divided into a number of sections by means of intermediate plates which may have the form shown in Fig. 8. In the drawing two plates 22, 23, 25 dividing the rheostat into three units, are shown by way of example, although a larger number of units may be provided.

The means for diminishing friction of the disks on the supports consists of the following arrangement. To limit the movement of plate 22 toward the compression end, stops or clamps 24 are adjustably secured to the rods 3 and 4. Two stops 25 are similarly arranged to limit the movement of the plate 23. Between the end 1 and plate 22 there will be placed enough resistance disks so that when plate 22 is adjacent stops 24, the pile of disks is expanded as much as it can be permitted to expand without danger of opening the circuit. The disks in the intermediate unit will be similarly packed. Each of the stops has a means, such as projecting hook 27, to engage one end of a spring 28 which passes through openings in the stops, the other end being fastened in any suitable manner to a projection 29 of the intermediate plates, for example by means of strips 30 shown in Fig. 7.

The means by which the sections may be placed in series or in parallel consists of two conducting rods 31, 32 on opposite sides of the rheostat, which pass through insulating bushings 9 in the end plates and provide terminals 34, 35 to which leads may be secured in any desired way. Electrical connection is made between the terminal rods on the one hand, and end contact plates 12, 12 and intermediate plates 22, 23 on the other, by means of spring clips 36, 37, 38 and 39 respectively (Fig. 1). These clips grip the rods in the manner shown fully in Figs. 8 and 9.

Each of the clips is connected by means of a flexible conductor or "pigtail" 40 to a projection 41 (Fig. 7) of the contact or in-

termidate plates. To permit the spring clips 36 and 37 to be moved simultaneously, they are fastened to a bar 42, and clips 38 and 39 are similarly fastened to a bar 43. The rod 32 is cut away on diagonally opposite faces at the point where the clip 36 grips the rod and at each of these cut away surfaces an insulating segment 44 is attached, as shown in Fig. 8. The position where clip 39 grips the rod is also insulated in the same manner at two points of its circumference. The shape of the clip is such that in the position shown in Fig. 9 it is insulated from the rod and by rotating it about 60 degrees around the contact bar it is in electrical contact therewith.

A spring 45 is fitted to each of the insulating bars 43 and cooperates with flat portions 46, 47 of the conductive rods to maintain the clips and bars in either of the two operating positions.

The rheostat may be manipulated in the following manner:—When the hand wheel 18 is turned the pressure is transmitted to the disks through the ball and socket joint described. As the disks are moved the plates 22, 23 are forced back from the stops against the pressure of the springs 28 which have no special function during this part of the operation. The resistance of the rheostat is thus decreased by compressing the disk in much the same manner as in prior types. However, the operation of the rheostat during the reverse movement of the hand wheel is decidedly different from that of prior types. In such prior types the disks near the compression end will readily slide along the supports, but before those at the other end can expand it is necessary to overcome the friction of all the rest of the disks on their supports. The frictional resistance to expansion therefore progressively increases in value toward the stationary end. Most of the disks thus remain under considerable pressure, especially in long piles. In cutting in resistance with my improvement, however, the disks in the first instance are forcibly moved along by the first set of springs, so that the disks in the second and third sections are relieved of the frictional resistance of the first set. The second set of springs likewise forcibly moves the disks in the second section, which relieves the disks in the third section of the corresponding frictional resistance. Each section in expanding therefore is independent of the frictional resistance of the other sections. The freedom of movement of the disks in the three section rheostat illustrated is therefore the same as that of the usual rheostat of one third the length. My improvement therefore permits a rheostat to be made of any desired length by adding with each additional section a set of springs and its co-operating parts.

While for purpose of illustration I have shown only two sets of springs in a three section rheostat, it will be apparent that any number may be added to produce any desired length of rheostat.

To further increase the range beyond that of the spring device, especially to decrease the resistance below that of all the sections in series when under compression, a simple arrangement is used to place the sections in parallel. To place the sections all in series the insulating bar 42 is turned to the position shown in Fig. 8 and the opposite bar 43, clip 37 and insulation 44 are also placed in similar electrical relations. The intermediate plates 22, 23, connected to clips 36, 39, are thus insulated from the bars 31, 32, and current passes from terminal 34 to clip 37, to front plate 12, through all the sections in series to rear plate 12, to clip 38, and thus to terminal bar 35.

When it is desired to place all the sections in parallel the bars 42, 43 are turned through an angle as illustrated in Fig. 9 to cause the clips 36, 39 to conductively engage the bars 31, 32. Clips 37, 38 remain continually in contact because no insulation is used at their points of contact with the bars. The circuit of the unit between stationary end 1 and plate 22 is from clip 38 on bar 35 to the plate 12, through the disks of the unit to plate 22 and to clip 36 on bar 34. The unit between the plates 22 and 23 is connected by clip 39, to bar 35, and by clip 36, to bar 34. By means of clip 39 and clip 38 the third unit is connected across the terminal bars, so that all three units are thus in parallel across bars 34, 35.

The detail view of Fig. 6 shows a method of preventing arcing at the point of contact of the edges of the disks, which would in time destroy the insulation of the supporting rod. This consists in beveling the disks either on one or both edges so that no arc can occur at the periphery of the disks close to the point of support. The beveling is only required at the point of support on rod 5, but the disk is preferably beveled all around its periphery so that no special care is required in placing the disks in position.

The staggered disks and rod supports provide a simple method of securing a good radiation because the passage of cooling air between the projecting surfaces is unimpeded. Renewals may be readily made with this arrangement and the elements are self-aligning.

Having described my invention, what I claim is:

1. In electric rheostats, a frame comprising end members and side members, a plurality of disks each having its surface in partial contact with the adjacent disks, and means for maintaining alternate disks adjacent different side members, whereby a

portion of each disk is in contact with an adjacent disk and the remainder of the disk serves as a heat radiating fin.

2. In electric rheostats, end members, side members connecting said end members, a member intermediate to the side members, a plurality of disks alined by the intermediate member and one of the side members, a plurality of disks alined by the intermediate member and the other side member, alternating with said first mentioned disks, and means for applying pressure to the disks.

3. In electric rheostats, end members, side rods connecting said ends, a rod intermediate thereto, a plurality of disks forming a pile, said disks being alternately placed in contact with the opposite side rods and the intermediate rod with the faces partially in contact, and means for applying pressure to the contact area.

4. In electric rheostats, oppositely placed vertical end members, horizontal side rods connecting the end members, a rod intermediate to the side rods, a plurality of circular disks supported between the intermediate rod and one side rod, a plurality of circular disks supported between the intermediate rod and the other side rod and alternating with the first mentioned disks whereby a portion of each disk serves as a resistor and the remainder serves as a radiating fin, and means for applying pressure to the resistance portion.

5. In an electric rheostat, a plurality of disks constituting a pile, compression means, and means for moving a section of the pile bodily toward the compressing end as the compressing force diminishes, whereby the adjacent section can expand without moving the first mentioned section.

6. In an electric rheostat, a plurality of disks constituting a pile, means for dividing the pile into a plurality of sections, compression means, and means coöperating with the first mentioned means to oppose the compression force and adapted to move a section of the rheostat in the opposite direction as the compressing force diminishes, whereby the adjacent section is permitted to expand as a simple rheostat of the same length as the section.

7. In an electric rheostat, end members, a plurality of disks constituting a pile, means for dividing the pile into a plurality of sections, side rods connecting said end members, means for applying pressure to the pile, and a spring attached to said first mentioned means and said rod, opposing the compression force.

8. In an electric rheostat, end members, side rods connecting said end members, a plurality of disks constituting a pile, means for dividing the pile into a plurality of sections, compression means, a stop connected to one of said rods, and a spring connected

- between said first mentioned means and said stop, adapted to oppose the compression force and move said first mentioned means against the stop.
5. 9. In an electric rheostat, end members, side rods connecting said end members, a plurality of disks constituting a pile, means for dividing the pile into a plurality of sections, compression means, adjustable stops attached to the rods and springs connected between said first mentioned means and said stops, said springs opposing the compression force and adapted to move said dividing means and section adjacent thereto, whereby 15 the section on the opposite side of said dividing means is permitted to expand without moving the first mentioned section when the compression is withdrawn.
10. In an electric rheostat, end members, side members connecting the end members, an intermediate member, a plurality of disks placed alternately on opposite sides of the intermediate rod but partially in contact, means for dividing the rheostat into a 25 plurality of sections, compression means and means for moving a section as the compressing force diminishes, whereby the adjacent section can expand without displacing said first mentioned section.
30. 11. In electric rheostats, end members, a plurality of disks forming a pile between said ends; means for dividing the pile into a plurality of sections, a conducting rod, and means for electrically connecting and disconnecting the dividing means and the rod.
12. In electric rheostats, end members, a plurality of disks forming a pile between said ends, means for dividing the pile into 40 a plurality of sections, a conducting rod, an insulating member attached thereto and means connected to said dividing means and adapted to contact alternately with said conducting rod or insulating member.
45. 13. In electric rheostats, end members, a plurality of disks forming a pile between said ends, means for dividing the pile into a plurality of sections, a cylindrical conducting rod having insulating segments attached thereto, a spring clip fitted on the rod and adapted to be rotated relatively thereto, and a flexible connection between said clip and dividing means.
50. 14. In electric rheostats, end members, a plurality of disks forming a pile between
- said ends, a metal plate for dividing the pile into sections, a cylindrical conducting rod having insulating segments attached thereto, a spring clip fitted on the rod and adapted to be rotated on the rod to contact either 60 with the conductive parts or the insulating segments of the bar and a flexible conductor connecting the plate and clip.
15. In electric rheostats, end members, a plurality of disks forming a pile between 65 said ends, a plurality of metal plates between said disks dividing the pile into sections, two conducting rods connecting said ends having insulating segments thereon, a plurality of spring clips on each of said 70 rods, flexible connections between said plates and said rods and means for rotating the clips on the rods.
16. In an electric rheostat, a frame comprising end members and side members, a 75 compressible pile between said ends, a compression plate for the pile, a ball adjacent thereto, a threaded rod passing through one of the ends and having a retaining socket 80 for the ball.
17. In an electric rheostat, a frame comprising end and side members, a compressible pile between said ends, a compression plate, a ball adjacent thereto, a retaining socket member for the ball, a threaded rod 85 passing through the end and connected to the socket member, and a hand wheel for turning the rod to apply pressure to the pile.
18. In electric rheostats, a frame comprising end members and side members, a compressible pile between said ends, a compression plate, a ball adjacent thereto, a socket member for the ball, a threaded rod passing 90 through an end member and connected to the socket member, and means connected to 95 the compression plate and the compression rod for moving said plate with the rod.
19. In electric rheostats, a frame comprising end members and side members, a compressible pile between said ends, a compression plate, a ball adjacent thereto, a socket member for the ball, a threaded rod passing 100 through an end member and connected to the socket, and a frame fastened to said plate adapted to engage said rod whereby 105 the compression plate is moved back and forth with the compression rod.

In testimony whereof I hereunto affix my signature.

EMERSON L. CLARK.
